*Primary Examiner—Celia Murphy
Attorney, Agent, or Firm—Weingram & Associates, P.C.*[57] **CLAIM**

I/we claim the ornamental design for a CD storage page, as shown and described.

DESCRIPTION

FIG. 1 is a perspective view of a compact disc (CD) storage page showing my new design according to the present invention.

FIG. 2 is a front elevation view of the design shown in FIG. 1, the opposite side being a mirror image thereof; FIG. 3 is a right side elevation view thereof; FIG. 4 is a left side elevation view thereof; and, FIG. 5 is a top plan view thereof, the bottom plan view being a mirror image thereof.
